(57) **CLAIM**

The ornamental design for a tubular member clamp, as shown and described.

DESCRIPTION

FIG. 1 is a top perspective view of a tubular member clamp showing our new design;

FIG. 2 is a rear elevational view thereof;

FIG. 3 is a front elevational view thereof;

FIG. 4 is a top plan view thereof;

FIG. 5 is a bottom plan view thereof; and,

FIG. 6 is a left side elevational view thereof, the right side elevational view being a mirror image.

The broken line showing of parts of the clamp is for illustrative purposes only and forms no part of the claimed design.
